PUMP, COMPRESSOR, AND SIMILAR
MACHINES

Frank Albert Laythorpe, deceased, late of Romford, England, by Annie Ellen Laythorpe, administratrix, Romford, England, assignor to L. V. B. Compressors Limited, Romford, England

Application January 3, 1938, Serial No. 183,170
In Great Britain January 8, 1937

2 Claims. (CL 103—138)

This invention relates to pumps, compressors and similar machines of the type employing a crescent-shaped working space provided between the periphery of a rotating drum eccentrically mounted within a casing, the working space being divided into a plurality of compartments by means of radial vanes slidably carried by said drum and adapted to advance or recede according to the differing space between the rotor periphery and the casing.

The present invention is concerned with improvements in the construction of this type of machine, the objects of which are to enable a machine, hitherto limited almost entirely to use as a low pressure pump or exhauster or blower, to be employed for high pressure duty or as a vacuum pump.

The improvements in sliding-vane machines provided in accordance with this invention result in a pump or compressor construction of high displacement efficiency, effective at all speeds and which has the advantage of dispensing with a packed gland when dealing with liquids.

The invention provides a pump, compressor or like machine of the sliding-vane type comprising a sectional casing having a working chamber of circular form in elevation and of substantially flat-sided rounded peripheral form in cross-section, a drum eccentrically mounted within the casing and having a shape similar to that of the casing (i. e. circular and substantially flat-sided with rounded periphery in cross-section), a plurality of transverse vane slots in the periphery of the drum, each slot accommodating one or more vanes having a contour complementary to the inner curved peripheral wall of the casing, curved packing members carried on the side walls of the drum between the adjacent vanes or sets of vanes and adapted to maintain contact with the casing interior.

Preferably, a two-part casing is employed which is constituted by a pair of flat-bottom cup members provided at their meeting edges or rims with a spigot or tongue-and-groove joint. In a pump or compressor for handling light liquids, air or other gases it is preferred to provide an even number of vane slots arranged in diametrical pairs so that the vane or vanes in one slot of the pair can be mechanically connected to the vane or vanes in the other slot of the pair. In machines for handling sludge or like dense liquids, this coupling together of diametrically opposite vanes is dispensed with, the vanes being free to make contact with the casing interior.

The present invention also provides for a novel vane assembly, the rounded peripheral portions of the vanes carrying curved packing members of half-ring form. These packing members are floatingly mounted on the vane peripheries and spring-pressed into contact with the casing wall. Each vane may be equipped with one or more packing rings.

One embodiment of this invention primarily intended for use as a fluid pump is illustrated diagrammatically in the drawings. These drawings also illustrate some modifications applicable to machines handling liquids and also details of the novel vane construction employed.

In the accompanying drawings:

Figures 1 and 2 are longitudinal and transverse sectional elevations of the water-cooled compressor.

Figures 3 and 4 are part-sectional front and side views of a pair of interconnected vanes.

Figure 5 is a fragmentary sectional view to an enlarged scale showing particularly the compensated mounting employed for three packing rings; and

Figure 6 is a modification hereinafter more particularly described.

The compressor casing shown in Figures 1 and 2 is constituted by a pair of double-walled cup-shaped half castings 1, 2, having a spigot joint 3 between the meeting or abutting edges of the castings. The castings 1, 2 are clamped together by bolts 4 and mounted on a hollow base or pedestal 5 forming an oil sump. The spaces 6 between the double walls of the castings 1, 2 form a water-jacket having inlet and outlet openings 7, 8 respectively, the water spaces of the castings 1, 2 intercommunicating by way of aligned openings 9 provided in the meeting faces of said castings.

Within the casing is concentrically mounted a drum or rotor 10 which is fixed to a power-driven shaft 11 journaled in ball bearings 12. The drum 10 has flat sides and a semi-circular periphery (in cross-section) and the working chamber 13 of the casing is of complementary shape. Four equidistantly spaced transverse slots 14 are provided in the drum 10, each housing a sliding vane assembly. The members of oppositely disposed pairs of vanes 15 are connected together by pairs of tie rods 16 pinned to the vanes. Each vane 15 (see Figures 3 and 4) is of flanged form and accommodates between its flanges 17 one or more packing or
